UNITED STATES PATENT OFFICE.

SAMUEL MUNDHEIM, OF NEW YORK, N. Y.

DESIGN FOR A HAT.

SPECIFICATION forming part of Design No. 35,660, dated February 4, 1902.

Application filed December 4, 1901. Serial No. 84,714. Term of patent 3½ years.

To all whom it may concern:

Be it known that I, SAMUEL MUNDHEIM, a citizen of the United States, and a resident of the city and county of New York, borough of Manhattan, and State of New York, (and whose post-office address is No. 20 East Ninety-seventh street, in said city,) have invented and produced a new and original Design for a Hat, of which the following is a specification.

10 In the drawings forming part of this specification, Figure 1 is a side elevation; Fig. 2, a plan view; and Fig. 3, a sectional elevation on the line 3 3, Fig. 1.

The essential feature of my invention relates in giving to the brim the configuration hereinafter described.

In the drawings, 1 is the crown of the hat of conventional shape, and 2 the brim. This is of conventional shape, except as hereinafter pointed out—that is, it is in plan view oval, with an upward and outward curve at

the sides 3 and a downward droop at the ends 4, the periphery of the brim being bent over inwardly, as at 5. Between the lower and upper edges of the brim, perpendicularly and between the ends, the brim is inset, as at 6—that is to say, while the brim at the sides is curved upwardly and outwardly it is between the points previously indicated and, as described, curved inwardly and upwardly, giving to the brim in end elevation and in plan a flattened appearance.

Having described my invention, I claim—
The design for a hat, substantially as herein shown and described.

Signed in the city, county, and State of New York this 2d day of December, 1901.

SAMUEL MUNDHEIM.
